BY BAKERWELL & CORNWALL ATT'Y'S.

UNITED STATES PATENT OFFICE.

JAMES E. ALLISON, OF ST. LOUIS, MISSOURI, ASSIGNOR TO DR. J. H. MCLEAN MEDICINE COMPANY, OF ST. LOUIS, MISSOURI, A CORPORATION OF MISSOURI.

DISPLAY-CASE.

No. 821,573.

Specification of Letters Patent. Patented May 22, 1906.

Application filed December 4, 1905. Serial No. 290,170.

To all whom it may concern:

Be it known that I, JAMES E. ALLISON, a citizen of the United States, residing at St. Louis, Missouri, have invented a certain new and useful Improvement in Display-Cases, of which the following is a full, clear, and exact description, such as will enable others skilled in the art to which it appertains to make and use the same, reference being had to the accompanying drawings, forming part of this specification, in which—

Figure 1 is a front elevational view of a display case or receptacle embodying the features of my invention. Fig. 2 is a rear elevational view of the case shown in Fig. 1. Fig. 3 is a sectional view taken on the line 3 3 of Fig. 1, and Fig. 4 is a sectional view taken on the line 4 4 of Fig. 1.

This invention relates to devices for displaying articles for sale; and the object of the invention is to provide a case or receptacle adapted to contain a number of articles, some of which are exposed to view, and which is provided with a locking device, which prevents any of the articles from being surreptitiously removed from the case. Devices of this character are used extensively in stores for displaying to the retail trade articles—such, for example, as boxes of cough-drops or matches. Heretofore the devices which have been in general use had no means for preventing a dishonest person from removing the articles therefrom, so that very frequently the displayed articles were stolen.

The device herein shown, which embodies the preferred form of my invention, prevents any of the articles therein from being surreptitiously removed, as said device is provided with a locking device that cannot be seen by the prospective purchaser, but which can be operated by the owner or clerk standing in the rear of the device to permit the articles to be removed therefrom.

Referring to the drawings, 1 designates the front wall of a case or receptacle, and 2 designates the rear wall thereof, said walls being provided with telescoping flanges 3 and 4, so that the case is constructed practically the same as a box. The rear wall is provided with a plurality of guides 5, which extend parallel to the side flanges and confine in position three rows of articles, herein shown as boxes 6. A guide-block 7 is also connected

to the rear wall 2 between one of the guides 5 and the right-hand side flange, as shown in dotted lines in Fig. 1 and in section in Fig. 4, and reciprocatingly mounted in said block is a locking device 8, preferably formed of wire and provided at its upper end with a finger-piece 9. A spacing-block 10 is interposed between one of the side flanges and one of the guides 5 of the rear wall at some distance above the guide-block 7, as shown in Fig. 4, so that a sufficient space is provided to allow the locking device to be moved upwardly, as hereinafter described. The guides 5 do not extend for the full height of the case, but terminate some distance from the lower flange of the rear wall, so that the lowermost boxes of the rows can be moved laterally in the direction of the arrow in Fig. 1 when the locking device is elevated, the lower portion of the right-hand flanges of the front and rear walls being cut away to provide a discharge-opening 16, through which the articles are removed. Preferably the front wall is provided with three openings 11, which expose to the view of the purchasers the lowermost box of each row, and the rear wall is provided with three longitudinally-extending slits 12, which enables the clerk to see the number of boxes in each row, said rear wall being also provided with a transversely-extending opening 13, in which the clerk inserts his finger to move one of the boxes laterally. The rear wall is also provided with an elongated opening 14, in which the clerk inserts his finger to engage the locking device 8 and move it upwardly into its inoperative position to permit one of the boxes to be removed. For holding the case or receptacle in an upright position legs 15 are secured to the rear wall 2.

From the foregoing description it will be seen that I have devised a display case or receptacle of simple construction which will expose to the view of the purchaser the kind of articles which are in the case and which is provided with means for preventing any of the articles from being removed surreptitiously. The row of articles nearest the discharge-opening will of course become exhausted first; but by moving one of the articles from the second row laterally the three openings in the front wall can be kept filled, it being understood that as an article is removed the one above it will automatically

drop into position. Preferably the case or receptacle is made of cardboard, so that it can be constructed at small cost by the manufacturer of the articles, and thus dispense with the necessity of using one receptacle for shipping the articles and a different receptacle for displaying the articles for sale to the retail trade. It should be understood, however, that the kind of material from which the case is constructed or the number of articles contained therein is immaterial so far as my invention is concerned.

Having thus described my invention, what I claim as new, and desire to secure by Letters Patent, is—

1. A display case or receptacle adapted to hold a number of articles and having a side wall provided with a discharge-opening, means for supporting said receptacle in an upright position, and a movable locking device for preventing an article from being removed through said discharge-opening when said locking device is in its operative position; substantially as described.
2. A display case or receptacle constructed to hold a number of rows of articles and having a side wall provided with a discharge-opening in alignment with the lowermost articles of the rows, and a movable locking device adapted to prevent an article from being moved through the discharge-opening when said locking device is in its operative position; substantially as described.
3. A display case or receptacle adapted to hold a number of articles and provided with front and rear walls, the front wall being pro-

vided with an opening to expose to view some of the articles in the receptacle and the rear wall being provided with an opening to expose to view a portion of each article in the receptacle, said receptacle having a side wall provided with a discharge-opening through which the articles are removed, and a locking device adapted to be operated from the rear of the receptacle for preventing the articles from being moved through the discharge-opening; substantially as described.

4. A display case or receptacle of box-like construction provided with a plurality of guides for holding in position rows of articles, the front wall of said receptacle being provided with openings for exposing to view the lowermost article of each row and one of the side walls of said receptacle being provided with a discharge-opening in alignment with the lowermost articles of the rows, and a locking device mounted in the receptacle and normally occupying a position to prevent an article from being moved through said discharge-opening, the rear wall of said receptacle being provided with an opening for enabling the locking device to be actuated and with a second opening for enabling the articles to be engaged and moved through the discharge-opening; substantially as described.

In testimony whereof I hereunto affix my signature, in the presence of two witnesses, this 25th day of November, 1905.

JAMES E. ALLISON.
